COLLET INDEX FIXTURE

Joseph Bochenek, Milwaukee, Wis.

Application April 8, 1942, Serial No. 438,063

3 Claims. (Cl. 90—57)

This invention appertains to a novel collet fixture for effectively holding and indexing stock while being worked upon by a milling, shaping, grinding, or like machine.

One of the primary objects of my invention is to provide a collet index fixture in which the work can be readily turned and quickly held in a selected position relative to the operating tool.

Another salient object of my invention is to provide a collet index fixture which merely embodies a base plate having a right-angularly extending wall or flange for rotatably supporting a hollow work-receiving shaft or spindle, with an adjustable collar at one end for gripping the work, and a dial index plate at its opposite end, and a sliding index pin or plunger movable through the wall or flange into a selected index opening in the dial plate for holding the spindle and work in a selected position.

A further important object of my invention is the provision of means whereby the dial plate and spindle can be accurately adjusted and locked relative to one another, whereby the work and spindle can be slightly turned relative to the set dial plate to facilitate certain operations or to correct slight errors in setting, which might occur.

A still further object of my invention is the provision of a rotatable spindle for receiving and gripping the work, having a lock collar on one end thereof for rotation therewith, and a dial index plate on the spindle adjustably connected with the collar, whereby the collar and spindle can be turned, within certain limits, relative to the dial plate, said adjustable connection permitting the collar and dial plate to be firmly bound together for synchronous movement.

With these and other objects in view, the invention consists in the novel construction, arrangement, and formation of parts, as will be hereinafter more specifically described, claimed, and illustrated in the accompanying drawing, in which drawing:

Figure 1 is a top plan view of my novel collet index fixture, showing the same used for holding a bar of solid stock in position relative to the tool of a milling machine, parts of the figure being shown broken away and in section to illustrate structural details.

Figure 2 is a central, longitudinal, sectional view through the fixture, taken on the line 2—2 of Figure 4, looking in the direction of the arrows.

Figure 3 is a sectional view through the work-

holding collet, taken on the line 3—3 of Figure 2, looking in direction of the arrows.

Figure 4 is a front elevational view of my novel collet index fixture.

5 Referring to the drawing in detail, wherein similar reference characters designate corresponding parts throughout the several views, the letter F generally indicates my novel collet index fixture. The fixture F is of a universal character and can be disposed in a horizontal or vertical position upon the bed or table of a metalworking machine.

10 The fixture can be used with milling machines, grinders, shapers, drill presses, and the like, and can be held in a vise, a magnetic chuck, or bolted to the table of any machine, and can be used for many different purposes.

15 In the present instance, I have shown a collet index fixture of the type for permitting the work 20 to extend therethrough. The work is indicated by the reference character W and is being operated upon by the tool 5 of a milling machine M for making a hexagonal bar.

25 As illustrated, the novel collet index fixture F includes a base plate 10 having formed on one edge thereof a right-angularly extending wall or flange 11. This wall or flange 11 has formed thereon an enlargement 12, which forms a bearing for rotatably receiving the hollow spindle 13. The spindle 13 extends entirely through the wall 11 and the bearing 12 and projects outwardly from the opposite sides of said wall. One end of the spindle 13 has formed thereon an enlarged hollow head 14, having a tapered inner 30 face 15 for receiving the split collet clamping ring 16. The outer surface of the split collet clamping ring 16 is tapered and is fitted within the hollow head 14. A collar 17 is threaded upon said head and is provided with an inturned annular flange 18 for engaging the split clamping 35 ring to force the same into said head for contraction about the work W. Hence, the work can be firmly and tightly clamped in said spindle and centered relative thereto. The outer face of the collar 17 can be provided at spaced 40 points with openings for the reception of a suitable handle or lever, whereby the collar can be turned.

45 Rotatably mounted upon the opposite end of the spindle is a dial index plate 19. Threaded upon the spindle adjacent the dial plate is a lock collar 20, and this collar can be firmly secured to said spindle by means of a machine screw 21. Rigidly connected to the collar 20 is an adjustment plate 22. This plate 22 can be riveted or

otherwise connected to the lock collar 20 by fastening elements 23. The adjustment plate 22 is relatively thin and has formed thereon a radially extending ear 24. This ear is provided with an arcuate slot 25, which is concentric with the axis of the spindle. The index dial plate 19 carries a set screw 26, which extends through the slot 25, and by tightening or loosening this screw, the dial plate and the spindle can be turned relative to one another to a limited degree. By this construction, it is obvious that the dial plate 19 can be accurately set on the spindle.

The dial plate is provided with an annular row of spaced openings 27, any one of which is adapted to be brought into registration with an opening 28 formed in the wall 11. A headed plunger or pin 29 is employed for movement through the opening 28 and into one selected opening 27. By this arrangement, the dial plate and the spindle and the work can be turned to a selected position 20 and held against movement.

Any predetermined number of openings 27 are provided, and in the present instance, the index plate is shown with twelve holes or openings to give two, three, four, six, eight, or twelve divisions, or 30° spacings.

As stated, the set screw employed for connecting the dial index plate with the lock collar can be loosened to permit inaccuracies to be taken care of.

From the foregoing description it can be seen that I have provided an exceptionally simple and durable collet index fixture, which will effectively perform its work.

Changes in details may be made, which do not depart from the spirit and scope of my claims, and what I claim as new is:

1. A collet index fixture comprising, a base plate, a right-angularly extending wall formed on the base plate having a bearing boss, a spindle 40 rotatable in the bearing boss and extending beyond both sides of the wall, a collet for the work carried by and rotatable with one end of the spindle, a dial index plate mounted on the other end of the spindle, a lock collar on said spindle 45 for holding the spindle against shifting move-

ment in the bearing boss, means connecting the dial plate with the lock collar, the index plate having a plurality of spaced openings therein, and said wall having an opening therein, and a 5 5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285
